SUBMARINE FLOATING BODY.

1,363,958.

Specification of Letters Patent. Patented Dec. 28, 1920.

Application filed August 14, 1916. Serial No. 114,796.

To all whom it may concern:

Be it known that I, GUSTAF DALEN, a citizen of the Kingdom of Sweden, residing at Skärsätra, Lidingön, Sweden, have invented new and useful Improvements in Submarine Floating Bodies, of which the following is a specification.

This invention relates to a submarine floating body, as for instance mine, torpedo or the like, which, when launched in the water, adjusts automatically its specific weight in strict accordance with the specific weight of the surrounding water and then stops at a certain depth of submersion, the body maintaining in this position a stable equilibrium by opposing, by means of automatic changes of the specific weight, outer impulses tending to bring the body out of equilibrium.

It has been proposed to construct submarine floating bodies keeping themselves at a certain middle depth of submersion by the bodies performing a continuous, oscillating movement up and down about a certain middle position, for instance by means of changes of the specific weight of the floating body effected under the control of a hydrostat in such a manner that said specific weight becomes alternately greater and smaller than that of the surrounding water.

Such submarine bodies consume a considerable amount of power for maintaining the movement, and the sources of power proposed in connection with said bodies—as for instance compressed air, electric accumulators and spring motors—require in general a rather complicated controlling mechanism or bring about various difficulties reducing the reliability of service of said bodies.

According to the present invention the amount of power is reduced to a minimum by such a construction of the controlling mechanism of the submarine floating body that it tends continuously to keep the floating body in equilibrium in the water. For this purpose the said mechanism, which in a well-known manner consists of a device adapted to vary the specific weight of the floating body under the control of a hydrostatic device, is so constructed, that the adjustment of the specific weight of the floating body is effected by means of said hydrostatic device in cooperation with the device controlled thereby. The hydrostatic device serves, when the depth of submersion of the floating body changes, to so start the device

effecting the changes of the specific weight of the floating body, that the specific weight of said body is increased during the upward movement and decreased during the downward movement, while the device for changing the specific weight tends at the same time to put itself out of operation. Thereby an accurately gaged control of the specific weight is obtained, and the changes are limited to a minimum for counteracting the motions. Owing thereto the motion is effectively retarded, and the tendency to oscillate is suppressed.

Preferably, the controlling mechanism is so constructed, that the changes of the specific weight of the floating body are effected in a certain ratio to the changes of the depth of submersion, so that a downward movement between two levels causes a certain decrease of the specific weight, while an upward movement between the same levels causes an equal increase of the specific weight. Thereby each depth of submersion will correspond to a certain specific weight of the floating body, which tends to be in equilibrium at a certain depth of submersion corresponding to the specific weight of the surrounding water.

The invention is illustrated in the accompanying drawings showing diagrammatically some embodiments thereof and in which:—

Figure 1 is a partial section of a subfloating mine, in which the source of power consists of a compressed gas operating by the aid of a liquid under pressure. Fig. 2 is a detail of the controlling mechanism shown in Fig. 1. Fig. 3 is a modified form of the apparatus shown in Fig. 1. Fig. 4 is a partial section of a floating mine provided with an electric battery and a motor serving as a source of power. Fig. 5 is a constructional form in which the source of power consists of a spring motor operating by the aid of a liquid under pressure.

Referring to Fig. 1, 1 denotes the floating body, 2 a diaphragm or piston or any other member operating in a similar manner, said member being exposed, at the one side, to the pressure of the surrounding water and, at the other side, to the pressure of a spring 3 or the like, thus forming a hydrostatic device, by means of which the mechanism described below for changing the specific weight of the floating body is controlled.

100

105

110

The said mechanism consists of a cylinder 4 containing a piston 5, which by a bell crank lever 6 and a link 7 is connected with a diaphragm 8 or the like exposed, at the outer 5 side, to the water pressure.

Opening into the cylinder 4 behind the piston is a piping 9 for a suitable pressure medium, as for instance a liquid contained in a receptacle 10 and acted upon by the 10 pressure of a gas adapted to be supplied from without by a pump or from a compressed gas receiver before launching the floating body, or to be supplied from a compressed gas receiver located in the floating 15 body. Serving as a member controlling the supply of pressure medium to the cylinder 4 is a slide valve 11 movable in a valve chest, or a three-way cock or the like controlled by the hydrostat 2. 12 denotes a 20 piping leading from the liquid receptacle 10 to the slide valve, and 13 denotes a discharge piping adapted to discharge liquid from the cylinder 4 into the interior of the floating body or, if desired, into a separate 25 container. The slide valve 11 is also controlled indirectly by the piston 5, which is connected with a rod or a frame 14 forming a support for the inner end of the spring 3. On account thereof the tension of the spring 30 depends on the position of the piston 5, and a change of said position without a corresponding change of the outer water pressure will cause a movement of the slide valve 11 from operative to inoperative position, in which latter the valve channel 15 Fig. 2, occupies a middle position between the ports devised in the valve chest for the 35 pipings 12 and 13.

The device described operates as follows, 40 it being supposed that the floating body from the beginning is in equilibrium at a certain depth of submersion. The cylinder 4 is in part filled with liquid and keeps the diaphragm 8 in such a projecting position, 45 that the specific weight of the floating body corresponds exactly to the specific weight of the surrounding water. The diaphragm 2 occupies a middle position and the slide valve is in inoperative position, as in Figs. 50 1 and 2. If the body now be moved downward by any outer force, the water pressure acting upon the diaphragm 2 increases, so that said diaphragm, on moving inward, moves the slide valve 11 to the right, thus 55 opening a connection from the receptacle 10 through the piping 12, the channel 15 and the piping 9 to the cylinder 4. Owing thereto, the piston 5 is moved farther outward and forces the diaphragm 8 still more 60 outward, so that the specific weight of the floating body decreases. At the same time the piston 5 acts through the frame 14 upon the spring 3, thus increasing its tension, and, on account thereof, the said spring 65 tends to move the diaphragm 2 back to the

middle position and at the same time to move the slide valve to inoperative position. If the above-named movement of the floating body be effected with not too great a rapidity, the decrease of the specific 70 weight takes place continuously in a certain ratio to the change of the depth of submersion, because the slide valve 11, owing to the coöperation of the diaphragm 2 and the piston 5, is kept in a position in 75 which the valve channel is slightly opened, while the piston 5 tends continuously to interrupt entirely the connection between the receptacle 10 and the cylinder 4 through the said channel, whereas the hydrostat, according as the outer water pressure acting upon the same increases, tends to open said connection. The more the floating body is moved downward by the outer force, the more its specific weight decreases and 80 the more it opposes the movement within the given possible limits of control. In a similar manner the specific weight increases successively during an upward movement caused by an outer force, the 85 diaphragm being forced outward by the spring 3 owing to the decrease of the outer water pressure and at the same time moving the slide valve to the left, thus connecting the cylinder 4 with the discharge piping 13 through the valve channel 15. The outer water pressure acting upon the diaphragm 8 forces simultaneously the piston 5 backward, accordingly as the liquid discharges through the valve channel 15 90 and the piping 13. When moving backward, the piston 5 decreases the tension of the spring 3 and, owing thereto, tends to interrupt indirectly the connection between the cylinder 4 and the discharge piping, 95 since the water pressure, on the decrease of the tension of the spring 3, is anew capable of moving the diaphragm 2 and the slide valve 11 back to their middle positions. As will appear from the aforesaid, 100 the floating body, when in equilibrium, opposes any movement caused by an outer force in vertical direction with a force increasing, accordingly as the movement increases. If the moving force ceases after 105 having effected a certain movement, the floating body still possesses a certain positive or negative buoyancy tending to move the body back to the original position of equilibrium, the movement being effectively 110 retarded by the water resistance. At the same time a continuous change of the specific weight takes place. If in this case the floating body, when reaching the position of equilibrium, still possesses a certain 115 inertia, it proceeds beyond said position, but the change of the specific weight goes on continuously, so that the movement is counteracted also on account thereof. When the body then returns, the slide 120

125

130

valve is reversed instantly, and owing thereto the change of the specific weight is limited to the value necessary for causing the body to return, whereas any positive driving force capable of maintaining an oscillating movement is not supplied to the floating body. Therefore, any oscillation of the body will be rapidly suppressed.

Movements out of the position of equilibrium, as is mentioned above, may be caused by accidental, vertical currents in the water. If, on the other hand, in any case a change of the specific weight of the water surrounding the floating body should take place, a positive or negative buoyancy is imparted to the body causing the body to ascend or to descend, and at the same time the specific weight of the body is successively increased and decreased, respectively, until the said weight again becomes equal to that of the surrounding water, the body then stopping in another position of equilibrium.

In the constructional form shown in Fig. 3 a hydrostat of known construction is used and is so constructed that its deflections are increased within the total extent of the regulation of submersion of the floating body. The coöperation between the hydrostat 2 and the piston 5 adapted to move the diaphragm 8 outward for adjustment of the slide valve 11 is in this case effected by means of a so-called three point regulation, the slide valve being connected with a rocking lever 16, one end of which is connected with the hydrostat, while its other end is connected with the piston rod 17. When the floating body descends, the deflection of the hydrostat is increased, and on account thereof the slide valve 11 raises, until connection is effected between the receptacle 10 containing water under pressure and the cylinder 4 through the piping 12, the valve channel and the piping 9. Thereby the piston 5 is moved downward thus moving the diaphragm 8 outward, so that the specific weight of the floating body decreases. At the same time the piston 5 operates the slide valve 11 by means of the lever 16 in such manner, that the latter tends to move the valve back to inoperative position. If, on the contrary, the floating body ascends, the hydrostat 2 is contracted thus moving the valve 11 downward and effecting connection between the cylinder 4 and the discharge piping 13. The outer water pressure acting upon the diaphragm 8 moves the same inward, according as the liquid is discharged from the cylinder 4, and at the same time the valve 11 is operated by the piston rod 17 and the lever 16 and, owing thereto, is moved to inoperative position. In other respects the manner of operation is similar to that of the embodiment shown in Fig. 1.

In the embodiment of the invention shown in Fig. 4 a reversible electric series motor is

used for effecting the changes of the specific weight of the floating body. The diaphragm 8 is connected with a threaded stem 18 provided with a nut 19 in the form of a worm wheel, which is prevented from moving vertically and gears with a worm 20 operated immediately or by means of a gear by the electric series motor 21. One pole of the battery 22 is connected with one of the brushes of the motor, while the other pole is in connection with a contact-arm 23 adapted to be turned by a hydrostat 2 in one direction or the other by the aid of a rack and pinion or any other suitable gear. The other brush of the motor is connected with the center 24 of the field-winding, while each of the end-terminals 25, 26 of the field-winding is connected with a contact 27 and 28 respectively attached to a pivotally mounted plate 29 and coöperating with the contact-arm 23. The movement of the plate 29 is effected by the mechanism serving to change the specific weight of the floating body, for instance by the plate being connected by means of a link 30 and a bell crank 90 lever 31 with the threaded stem 18.

The manner of operation is as follows. When the floating body is in a position of equilibrium in the water, the diaphragm 8 is moved outward to such an extent, that the specific weight of the floating body is quite equal to that of the surrounding water. The contact plate 29 is kept in a corresponding position, and the contact arm 23 is retained by the hydrostat in an inoperative position between the two contacts 27 and 28. If the body be caused to descend, the hydrostat 2 is moved inward thereby turning the contact arm 23, so that it comes in contact with the contact 27. On account thereof the motor 21 is started in such a direction, that the diaphragm 8 is moved outward, and the specific weight of the body is reduced. Owing thereto a force counteracting the movement is effected. At the same time the plate 29 is turned by the aid of its connection with the stem 18, so that the circuit is broken, as soon as the downward movement of the floating body in the water ceases, and on account thereof the inward movement of the hydrostat ends. If, on the contrary, the floating body ascends, the hydrostat 2 is contracted, so that the contact arm 23 is brought in connection with the contact 28. Owing thereto the motor is started in the opposite direction, the diaphragm 8 is retracted, the specific weight of the body is increased and, consequently, the movement is counteracted. At the same time the plate 29 is turned in the same direction as the contact arm 23, so that the contact between the contact 28 and the arm 23 ceases, as soon as the floating body stops, and owing thereto the outward movement of the hydrostat ceases. If the movement was caused accidentally, for in-

stance by a current in the water, the floating body returns to the original position of equilibrium immediately or after a few oscillations with decreasing amplitude, as soon as the cause ceases. If, on the other hand, the cause was continuously acting, as for instance in case of a change of the specific weight of the surrounding water, the floating body remains in equilibrium in the new position, as was the case with the mechanically controlled floating body described above with reference to Fig. 1.

The floating body shown in Fig. 5 differs from that shown in Fig. 3 only in that the pressure acting upon the liquid contained in the receptacle 10 is effected by means of a piston 33 actuated by a spring motor 32 instead of by a compressed gas. The spring motor 32 which may be wound up by means of a crank placed on the pin 34 is by suitable means connected with a nut 35 in the form of a toothed wheel, said nut being screwed onto the threaded rod 36 of the piston 33 thus serving to move the piston forward, according as the liquid under pressure is consumed. The construction and manner of operation of the controlling mechanism proper are similar to those of the embodiment shown in Fig. 3.

The invention is not limited to the constructional details shown in the drawings, but may be varied in many different manners. Thus for instance for the diaphragm 8 effecting the changes of the specific weight of the floating body may be substituted a piston or a receptacle connected with the outer water or any other suitable device. For the slide valve shown in Fig. 1 may be substituted a three-way cock, and for the same valves shown in Figs. 3 and 5 may be substituted two valves placed one above the other or a three-way cock having a pivotally mounted casing, the hydrostat actuating in the two latter cases the one member for opening the connection to or from the working piston, while the other member is actuated by the device changing the specific weight and serves to interrupt the connection. Though a liquid under pressure is very suitable as a power transmitting means in the embodiments shown in Figs. 1 and 3, owing to the facility of controlling the current of a liquid and its incompressibility, nothing prevents, however, principally the direct use, in a subfloating body according to the invention, of compressed gas as a driving medium for effecting the necessary changes of the specific weight, as is the case with some types of oscillating subfloating bodies.

Having now described my invention, what I claim as new and desire to secure by Letters Patent is:

1. A submarine floating body adapted to assume a position of equilibrium at a certain

depth of submersion, comprising means for changing the specific weight of said body, a hydrostatic plate acted upon by the outer water pressure, a spring counteracting the water pressure on said plate, a controlling member assuming inoperative position in the position of equilibrium of the floating body and adapted to be actuated by said hydrostatic plate, so as to start the means changing the specific weight, and a connection between the said latter means and the said spring for varying the tension of the latter.

2. A submarine floating body adapted to assume a position of equilibrium at a certain depth of submersion, comprising means for changing the specific weight of the body consisting of a movable member adapted to be actuated in one direction by the outer water pressure, a liquid pressure cylinder, a container for liquid under pressure, a hydrostatic device, and a member controlling the supply of liquid from said container to the cylinder and its discharge from the cylinder, said controlling member being actuated in opposite directions by the hydrostatic device and the means for changing the specific weight of the body and means for varying the normal effective force of the hydrostatic device.

3. A submarine floating body adapted to assume equilibrium at a certain depth of submersion, comprising a hydrostat, a motor opposing the operation of the hydrostat, resilient means between the motor and hydrostat to permit compensating movements of either, and displacement varying means operated by the motor.

4. A submarine floating body adapted to assume a certain depth of submersion, comprising a hydrostat, a motor opposing operation of said hydrostat, resilient means between them, a valve operated by the differential movement between said motor and hydrostat and controlling a supply of motive fluid under pressure to said motor, and displacement means operated by the motor.

5. In a submarine floating body adapted to assume a position of equilibrium at a certain depth of submersion, the combination of a hydrostat, means for varying the specific weight of the said floating body, a connection between the said hydrostat and the said means, said connection comprising a movable member, the movements of which are controlled by the coöperation of the said hydrostat and the specific weight varying means, and a yielding device interposed between the said hydrostat and the specific weight varying means, said yielding device coöperating to control the action of the said hydrostat.

6. In a submarine floating body adapted to assume a position of equilibrium at a certain depth of submersion, the combina-

tion of a hydrostat, a diaphragm the outer surface of which is subjected to the pressure of the water within which the said floating body is situated which pressure tends to move the said diaphragm inwardly, means 5 for actuating the said diaphragm in a direction opposite to said pressure, a connection between the said hydrostat and the said diaphragm, a valve interposed in said connection, 10 means whereby the said hydrostat tends to move the said valve into operative position in one direction and means whereby a part of the said connection tends to move the said valve in the opposite direction into 15 inoperative position.

7. In a submarine floating body adapted to assume a position of equilibrium at a certain depth of submersion, the combination of a hydrostat, a movable diaphragm for 20 varying the specific weight of said body, a cylinder, a receptacle containing a fluid under pressure, a conduit for connecting said receptacle with said cylinder, a valve casing interrupting the said conduit, a valve operating in said casing, a connection between 25 said valve and said hydrostat, a piston adapted to operate in said cylinder, a member having connection with said piston being slidably connected with the connection between 30 the said hydrostat and the said valve, a yielding member interposed between the said hydrostat and the said member and means operatively connecting the said diaphragm with the said piston, substantially 35 as described.

8. A submarine floating body adapted to assume a position of equilibrium at a certain depth of submersion, comprising a hydrostat, a power actuated member, 40 connections between said member and said hydrostat whereby the said member and hydrostat may act upon each other with opposing forces and means under the control of said hydrostat for controlling the action of said 45 power actuated member, a movable member

for varying the displacement of said body, and connections between said movable member and the connections between the said hydrostat and said power actuated member whereby the position of said movable member is controlled by the said connections. 50

9. A submarine floating body adapted to assume a position of equilibrium at a certain depth of submersion, comprising a hydrostat, a displacement varying member, a 55 movable member operatively related to the said hydrostat, a valve member having connection with the said hydrostat, means for supplying a fluid under pressure to actuate said movable member, the passage of 60 fluid to said movable member being controlled by the said valve and connections between the said displacement varying member and the said movable member whereby the position of the former is controlled by 65 the position of the latter.

10. A submarine floating body adapted to assume a position of equilibrium at a certain depth of submersion, comprising a hydrostat, a displacement varying member, a 70 piston operated in a cylinder, operative connections between the said piston and the said hydrostat, said connections comprising a yielding device, a valve, a connection between said valve and said hydrostat, means 75 for supplying a fluid under pressure to the cylinder to operate said piston, the supplying of fluid to said cylinder being regulated and controlled by the said valve and operative connections between the said displacement varying member and the said piston whereby the position of the latter controls 80 the position of the said displacement varying member.

In testimony whereof I have signed my 85 name.

GUSTAF DALÉN.
